UNITED STATES PATENT OFFICE.

HERMAN WITKOWSKI, OF CHICAGO, ILLINOIS.

FLOOR-SCRAPER.

1,181,815.

Specification of Letters Patent. Patented May 2, 1916.

Application filed July 10, 1915. Serial No. 39,135.

To all whom it may concern:

Be it known that I, HERMAN WITKOWSKI, a citizen of the United States, residing at Chicago, in the county of Cook and State of Illinois, have invented certain new and useful Improvements in Floor-Scrapers; and I do hereby declare the following to be a full, clear, and exact description of the invention, such as will enable others skilled in the art 10 to which it appertains to make and use the same, reference being had to the accompanying drawings and to the letters and figures of reference marked thereon, which form a part of this specification.

15 This invention relates to new and useful improvements in floor scrapers and comprises a simple and efficient device of this nature having various details of construction, combinations and arrangements of 20 parts which will be hereinafter fully described, shown in the accompanying drawings and then specifically defined in the appended claim.

My invention is illustrated in the accompanying drawings, in which:

Figure 1 is a perspective view of the invention. Fig. 2 is a central longitudinal sectional view. Fig. 3 is a plan view of the inside of the clamping member A, and Fig. 30. 4 is a like view of the clamping member K. Reference now being had to the details of the drawings by letter, A designates one of the clamping jaws which is provided with a contracted extension B about which projects a flange D. The upper surface of said clamping jaw is provided with serrations E and is apertured at F for the reception of the bolt G upon which a winged nut H is mounted. The other jaw, designated by letter K, has a contracted extension K' adapt-

ed to conform to and engage the contraction upon the other jaw and is held from lateral movement by said flange. The jaw K is provided with a socket N for the reception of the handle O and has a slotted recess R 45 upon its clamping face adapted for the reception of the head of said bolt. Said clamping face is provided with transverse serrations C, coöperating with the serrations upon the other jaw to hold the scraping 50 member T.

It will be noted that the space intermediate the socket member and the projecting portion of the jaw K is concaved as at Q and adapted to receive the thumb of an 55 operator holding the device.

What I claim to be new is:

A floor scraper comprising a jaw with a corrugated face and provided with a recess with a slot in the wall thereof, a socket for 60 the reception of a handle, said jaw being disposed at an angle to the socket and having a contracted portion at one side of the latter, a second jaw having a contracted end corresponding to the shape of the contracted portion of the other jaw and provided with a flange extending about the contracted end and projecting beyond the inner face thereof and adapted to engage over the contracted end of the socket carrying 70 jaw, a bolt carried by the second referred to jaw and engaging the slot and recess in the other jaw.

In testimony whereof I hereunto affix my signature in presence of two witnesses.

HERMAN WITKOWSKI.
